UNLOADING MECHANISM FOR
COMPRESSORSGeorge F. Pfeifer, Quincy, Ill., assignor to Quincy
Compressor Co., a corporation of Illinois

Application April 30, 1935, Serial No. 19,098

9 Claims. (Cl. 230—26)

This invention relates to compressors and has for an object to provide fluid pressure operated means controlled by the governor to hold the compressor unloaded until the compressor reaches full speed.

A further object is to provide unloading mechanism which will permit of a lag or definite delay of the escape of the operating air so that the compressor is held unloaded for a short time after reaching full speed.

A further object is to provide unloading mechanism which will permit of an instantaneous action of the fluid pressure controlling valve when the pressure reaches a predetermined point at which the motor is automatically stopped to permit the compressor to come to a free unloaded rolling stop.

A further object is to provide unloading mechanism which may be applied to two stage as well as single stage compressors and when used on two stage compressors will simultaneously hold the high pressure intake valve open and at the same time vent the intercooler which connects the discharge of the low pressure cylinder to the high pressure intake, to the atmosphere so that a one hundred per cent unloading is effected.

A further object is to provide quick acting mechanism of this character which will be formed of a few, simple parts and which will be automatic in operation, will not require attention, and will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

40 In the accompanying drawings forming part of this specification,

Figure 1 is a fragmentary side elevation of a two stage compressor equipped with unloading mechanism constructed in accordance with the invention and shown in section.

Figure 2 is a front elevation of the parts shown in Figure 1.

Figure 3 is a longitudinal sectional view through the three-way valve.

50 Figure 4 is a detail sectional view showing a modified form of the invention.

Figure 5 is a detail sectional view showing a valve for causing a lag in one direction in flow through the fluid pressure pipe.

55 Referring now to the drawings in which like

characters of reference designate similar parts in the various views, 10 designates the crank case of a two stage compressor, 11 the crank shaft thereof, 12 the low pressure cylinder, and 13 the high pressure cylinder, the discharge of the low pressure cylinder being as usual connected by an intercooler 14 to the intake of the high pressure cylinder. A centrifugal governor 15 is mounted on the crank shaft 11, the governor weights as usual moving outwardly when the compressor is running and moving inwardly when the compressor stops.

In carrying out the invention I provide a stem 16 which is slideably fitted in a counterbore 17 formed in the end of the crank shaft and projects into a slot 18 in the crank shaft where it is connected to a bar 19 which is terminally equipped with pins 20 that extend through the collar 21 of the governor and are terminally equipped with rounded heads 22 which are held against the governor weights by a spring 23 which surrounds the stem 16 and is confined under tension between the end wall 24 of the counterbore and a stop collar 25 carried by the stem. As the weights are thrown out by centrifugal force 25 the stem is withdrawn by the bar 19 into the counterbore and as the weights move inwardly the spring 17 returns the stem to initial position. The movement of the stem 16 by the centrifugal governor is utilized to automatically unload the 30 cylinders every time the compressor is stopped. Unloading is accomplished by holding the intake valve of the compressor off its seat, and if the compressor is a two stage type, as illustrated, the air in both cylinders and intercooler is released to the atmosphere.

By now referring to Figure 1 it will be seen that a diaphragm 26 is mounted in a valve casing 27 which is disposed on the high pressure cylinder 13 and on one side of the diaphragm a plunger 28 is mounted in the casing and the stem 29 of the plunger is aligned axially with the high pressure intake check valve 30. When compressed air is admitted to the diaphragm valve casing 40 the diaphragm will be distended and move the plunger to engage and hold open the intake valve 30 so that the cylinder can not pump. At the same time the air from the low pressure cylinder enters the intake port 31 of the valve casing 27 as indicated by the arrow head in Figure 1 and is 45 vented to the atmosphere as will now be described. The stem 29 is equipped with a conical valve 32 which seats on a similar shaped seat 33 formed in an axial passage 34 in the valve casing 27. Vent openings 35 are formed in the casing 50

above the valve 32. When air pressure is applied to the diaphragm the plunger moves downwardly as above described to open the high pressure intake valve 30 and at the same time the valve 32 will be unseated and permit the air from the low pressure cylinder, entering through the intercooler 14, to pass longitudinally of the casing through ports in a bushing 36, around the valve 32, and into the atmosphere through the ports 35. In this position of the parts air is swept in and out of the high pressure cylinder through the open intake valve 32 and escapes through the openings in the bushing 36 and from thence through the ports 35 into the atmosphere. A spring 37 surrounds the stem of the plunger and is seated in a housing 38 carried by the bushing 36. The spring closes the conical plunger valve 32 and returns the plunger to initial position when air pressure is removed from the diaphragm, the plunger stem at the same time moving away from the high pressure intake valve to permit the valve to function.

Compressed air is supplied to the diaphragm valve casing on one side of the diaphragm through a pipe 39 which is connected to a three-way valve casing 40, compressed air being supplied to the valve casing through a pipe 41 which is connected to the compressed air receiver or tank not shown. The three-way valve housing 30 is substantially cruciform in contour as best shown in Figure 3, two of the aligned branches 42 and 43, being connected to the pipes 39 and 41 by screw threaded connectors 44 and 45, and the other two branches having seated therein valves 46 and 47 which are disposed in alignment with the above described stem 16 of the centrifugal governor. The valve 46 is faced with packing material 48 so as to seat tightly against a seat 49 and seal an axial duct 50 when the valve 40 is closed. A threaded cap 51 is screwed on to the valve housing to house the valve and the cap is provided in the end wall with a vent opening 52 through which air is released from the diaphragm valve above described as will presently be explained.

The valve 47 is likewise faced with packing material 53 to fit tightly against a seat 54 formed at the opposite end of the axial duct 50. A spring 55 is housed in a threaded plug 56 screwed into the valve housing and exerts pressure against the valve 47 to normally hold the valve closed.

A duct 57 is formed in the housing at a right angle to the axial duct 50 and connects the axial duct with the pipe 39. A duct 58 is formed in the housing and connects the pressure supply pipe 41 with a chamber 59 which houses the valve 53. The stems of both valves 46 and 47 are provided with frusto-conical tips 60 which abut each other at the duct 57.

By now referring to Figure 1 it will be seen that when the compressor is stopped the governor weights are disposed inwardly and the spring 23 forces the governor stem 16 against the valve 46 holding the valve closed and simultaneously holding the valve 47 open so that the air pressure from the pipe 41 passes through the duct 58, chamber 59, duct 50, duct 57 and pipe 39 to distend the diaphragm and hold the conical valve 32 open and the high pressure intake valve 30 unseated. In this position of the parts the cylinders are unloaded. When the compressor is started the unloaded condition is maintained sufficiently long to permit the motor and the compressor to come to full speed and when full speed is reached the governor weights 15

have moved outwardly and withdrawn the stem 16 from contact with the valve 46 so that the spring 55 acts on the valve 47 to close this valve and shut off the air supply to the diaphragm chamber through the port 58 and at the same time will open the valve 46 to unseal the axial port 50 and permit air entrapped in the pipe 39 and diaphragm valve casing to bleed through the duct 57, axial duct 50 and port 52 into the crank case of the compressor as best shown in Figure 1.

It does not require a long time for the governor weights to reach extreme outer position and to prevent the load coming on the motor too suddenly, the stem 61 of the valve 46 is a close fit and thereby restricts the flow of air from the diaphragm valve assembly, thereby holding the compressor unloaded for a short time even after the motor has come to full speed. The stem 62 of the valve 47 is provided with a flat side 63 which permits quick passage of the air through the duct 57 into the pipe 39 to promote rapid action when stopping. In practice, the governor weights move inwardly after a speed of 300 R. P. M. is reached, thereby permitting the compressor to come to a rolling stop. During the period from 300 R. P. M. to a complete stop, the low pressure piston is doing compression work, but this air is expelled through the intercooler 14 and out through the ports 31, 36 and 35 in the diaphragm valve assembly.

While the valve stems 61 and 63 respectively prevent the load coming on too suddenly, and promote rapid unloading when stopping, the same purpose may be accomplished by the check valve mechanism shown in Figure 5 which may be connected to the pipe 39 to give free flow in one direction and restricted flow in the opposite direction. In this modification the valve casing 65 is provided with an axial passage 66 of rather large diameter in which is mounted a check valve 67 which closes toward the three-way valve 40 and seats on a tapered seat 68, the valve being provided with wings 69 below the seat which form a bearing for the valve. A spring 70 is confined in a recess 71 formed in a cap nut 72 which is threaded into one end of the casing 65, the spring exerting pressure upon the valve 68 to normally hold the valve seated. Air let into the pipe 39 by the three-way valve to the diaphragm valve assembly will unseat the valve 67 and pass quickly to actuate the diaphragm valve.

A by-pass 73 is formed in the casing 65 to connect the ends of the passage 66 around the check valve 67, and a needle valve 74 is threaded into the side of the casing and enters the by-pass. Venting of the air from the pipe 39 through the by-pass 73 around the closed check valve 67 is thus restricted to hold the compressor unloaded for a short time after the motor has come to full speed. The axial passage 66, when the check valve 67 is opened, gives rapid action when stopping. A lock nut 75 is threaded on to the needle valve 74 to hold the needle valve in adjusted position.

A further modification of the invention is shown in Figure 4 in which the diaphragm valve assembly is dispensed with and the three-way valve 40 is connected by a pipe 76 to a check valve assembly 77 which communicates direct with the bore of the high compression cylinder through a lateral duct 78. The check valve assembly comprises a cruciform casing 78 which is provided in the lateral branches with air vents 79 that communicate with an axial passage 80 75

in the aligned branches. A valve 81 is housed in a valve casing 82 which is threaded on to the outer branch of the cruciform casing and is provided with a packing member 83 which engages with the valve seat 84 and forms a tight fit. The valve is provided with a stem 85 which is slidably fitted in the axial passage 80 and is equipped with a frusto-conical valve 86 which opens toward the cylinder and seats on a conical seat 87 as shown. A spring 88 surrounds the valve stem and holds the conical valve normally closed and the valve 81 normally open.

Air let into the pipe 76 by the three-way valve will act against the valve 81 and close the valve, 15 at the same time opening the valve 86 whereby the high pressure cylinder 89 will be vented to the atmosphere through the passage 78, around the valve 86, and through the vent ports 79, thus unloading the compressor. When the air is shut off by the three-way valve from the pipe 76 the 20 spring 88 will close the conical valve 86 and open the valve 81 which is the position of the parts when the compressor is pumping.

From the above description it is thought that 25 the construction and operation of my invention will be fully understood without further explanation.

What is claimed is:

1. In a two stage compressor, high and low pressure cylinders, an intercooler connecting the discharge port of the low pressure cylinder with the intake port of the high pressure cylinder, a diaphragm valve adapted to simultaneously unseat the high pressure cylinder intake valve unseated and vent the low pressure cylinder and the intercooler to the atmosphere, a governor, and means controlled by the governor for admitting a fluid pressure medium to operate the diaphragm valve.
2. An unloading device for compressors comprising a cylinder, a governor having a stem moved axially by opening and closing of the governor weights, a diaphragm valve in the cylinder for venting the cylinder to the atmosphere, a pipe for supplying a fluid pressure medium to the diaphragm valve to hold the valve open, a three-way valve casing in the pipe, and aligned valves in the casing spring pressed in one direction to vent the pipe and moved in the opposite direction by the governor stem to hold pressure in said pipe and actuate the diaphragm valve.
3. An unloading device for compressors including a cylinder, a governor, a diaphragm valve adapted to simultaneously unseat the cylinder intake valve and vent the cylinder to the atmosphere, a fluid pressure pipe for conducting a fluid pressure medium to the diaphragm valve, a three-way valve in the pipe controlled by the governor to admit a fluid pressure medium to the diaphragm valve to actuate the valve, and a spring controlling the three-way valve to vent the fluid pressure medium from said pipe.
4. The combination with a compressor, of a governor, a diaphragm valve controlling the intake of the compressor to load and unload the compressor, a three-way valve controlled by the

governor to alternately supply a fluid pressure medium to the diaphragm valve for opening the valve and to release the fluid pressure medium from the diaphragm valve for closing the valve, and means for restricting flow of the fluid pressure medium in one direction to delay loading the compressor.

5. The combination with a compressor, of a governor, a diaphragm valve controlling the intake of the compressor to load and unload the compressor, and a three-way valve assembly having aligned valves controlled by the governor to alternately supply and release a fluid pressure medium from the diaphragm valve for opening and closing the diaphragm valve, one of the aligned valves restricting the flow of the fluid pressure medium from the diaphragm valve to delay loading the compressor until a predetermined speed has been reached.

6. The combination with a compressor, of a governor, a diaphragm valve controlling the intake of the compressor to load and unload the compressor, a three-way valve assembly having aligned valves controlled by the governor to alternately supply and release a fluid pressure medium from the diaphragm valve for opening and closing the diaphragm valve, one of the aligned valves having a flat side for accelerating flow of the fluid pressure medium to the diaphragm valve to hasten action of the diaphragm valve in unloading the compressor.

7. The combination with a compressor, of a governor, a diaphragm valve controlling the intake of the compressor to load and unload the compressor, a three-way valve controlled by the governor to alternately supply a fluid pressure medium to the diaphragm valve for opening the valve and to release the fluid pressure medium from the diaphragm for closing the valve, and a check valve associated with the three-way valve having a by-pass restricting release of the fluid pressure medium from the diaphragm valve.

8. The combination with a compressor, of a governor, a three-way valve controlled by the governor, a check valve assembly for venting the compressor cylinder to the atmosphere, and a pipe connecting the three-way valve with the check valve assembly, said three-way valve being adapted to alternately supply a fluid pressure medium through the pipe to open the check valve and to release the fluid pressure medium from the pipe to close the check valve.

9. The combination with a compressor, of a centrifugal governor, a stem moved by the governor weights, a three-way valve casing, aligned valves in the casing moved in one direction by the governor stem and spring pressed in the opposite direction when the governor stem recedes, a valve assembly adapted to vent the compressor cylinder to the atmosphere, a pipe for supplying a fluid pressure medium to the three-way valve casing, and a pipe connecting the three-way valve casing with said valve assembly for supplying and releasing the fluid pressure medium from the valve assembly.

GEORGE F. PFEIFER.
